DISPLAY STAND

Joseph J. Trogan, 904 S. Michigan,
Saginaw, Mich. 48602

Filed Oct. 23, 1965, Ser. No. 87,844

Term of patent 14 years

(Cl. D80—9)

Fig. 1

Fig. 3

Fig. 2

Fig. 4

Fig. 5

Fig. 6

Fig. 8

Fig. 7

I claim:

The ornamental design for a display stand, as shown and described.
